US00D607489S

(12) United States Design Patent
Kida et al.

(10) Patent No.: US D607,489 S
(45) Date of Patent:  Jan. 5, 2010

(54) STAMP

(75) Inventors: Masaki Kida, Setagaya-ku (JP);
Motohide Imaizumi, Setagaya-ku (JP)

(73) Assignee: Shachihata Inc., Aichi (JP)

() Term: 14 Years

(21) Appl. No.: 29/311,048

(22) Filed: Dec. 16, 2008

(30) Foreign Application Priority Data

Jul. 2, 2008 (JP) D2008-017095

(51) LOC (9) Cl. 19-02

(52) U.S. Cl. D18/15

(58) Field of Classification Search D18/15-18;
101/333, 334, 327, 328, 352.07, 405, 406;
118/264, 268

See application file for complete search history.
